UNITED STATES PATENT OFFICE.

CLARENCE SCHOCK, OF MOUNT JOY, PENNSYLVANIA.

RECEPTACLE.

1,267,910.

Specification of Letters Patent. Patented May 28, 1918.

Application filed March 6, 1917. Serial No. 152,779.

To all whom it may concern:

Be it known that I, CLARENCE SCHOCK, a citizen of the United States, residing at Mount Joy, in the county of Lancaster and State of Pennsylvania, have invented certain new and useful Improvements in Receptacles, of which the following is a specification.

This invention relates to receptacles for oil and the like, and it comprises a receptacle of tin or the like, surrounded by a wooden casing, the casing being cut away throughout a portion, of the upper surface, to produce, in effect, a recess in said surface, a guard or protecting plate for the exposed face of the recessed portion, and a pouring neck arranged within the recess with the upper end of the pouring neck terminating below the outer surface of the casing. Within the pouring neck there is provided a plurality of radially disposed arms which support a centrally disposed stud. The cap of the receptacle is provided with a screw received by the stud when the cap is in position. The screw may be secured to the cap or may be separable, permitting movement of the screw without revolving the entire cap. A vent tube or passage extends from the neck toward the opposite side of the receptacle. The air tube is supported by the radially disposed arms, the arms being spaced to receive the tube and defining the pouring section and the vent section of the neck. Under some circumstances, it is advantageous to employ a nozzle or pouring spout, and the invention further comprises the provision of a detachable spout having a central screw received by the centrally disposed stud. The screw may be rigidly attached to the spout, but I find it advantageous to employ a loose screw passing through a central opening in a spider or other supporting arrangement within the spout.

The use of containers having threaded openings for the reception of a screw-threaded cap is known, but such devices have been only partially satisfactory, in view of the difficulty of making such threads accurate enough or of small enough gage to cause an even pressure of the cap on the washer at all points of the circumference. It is also desired to provide a vent passage permitting entrance of air to the interior of a receptacle but means for satisfactorily fastening the vent tube in the opening and confining the

passage of liquid from the receptacle to a space removed from the mouth of the tube have not been advanced. Further difficulty in the use of containers of a large type heretofore known is the impossibility of satisfactorily packing a number of such containers for shipping, due to the projection of the pouring neck above the surface of the edge of the container, or the like.

In the present invention I have provided a receptacle having means for securely fastening the cap in position and have utilized the fastening means for the purpose of supporting the vent tube and also to define passages for the outlet of the liquid and for the admission of air to the mouth of the vent. The receptacle is further constructed to permit packing of a large number without the usual attending difficulties through the provision of a recess in the top surface and the arrangement of the pouring neck with its upper end below the surface of the top of the receptacle.

In the present construction I employ a receptacle comprising an inner lining of tin, or other suitable material and an outer casing of wood, fiber or the like, the top of the casing being cut away to provide, in effect, a recess in which the pouring neck is situated, the pouring neck terminating below the surface of the outer casing. A guard or

protecting plate is arranged within the recess and is made of sheet metal, or other material of greater strength than the inner lining of the receptacle, the guard serving to hold the neck in position and extending beyond one edge of the receptacle to provide a pouring trough. Within the pouring neck there is provided a centrally disposed stud supported by a plurality of arms secured to the side of the neck. The cap carries a screw which is received by the stud and which fastens the cap in position. A vent tube is arranged within the receptacle extending from the neck toward the opposite edge, the outer end of the vent tube being secured between a pair of the supporting arms which are spaced to surround the same and define

passages for the flow of liquid from the receptacle and for the admission of air to the vent tube.

In the accompanying drawings I have illustrated an advantageous embodiment of this invention.

In the drawings—

Figure 1 is a perspective view of the receptacle;

Fig. 2 is a central sectional view taken 5 on the line 2—2 of Fig. 1;

Fig. 3 is a top plane view of the pouring neck and the vent tube removed from the receptacle;

Fig. 4 is a detail sectional view taken on 10 the line 4—4 of Fig. 2;

Fig. 5 is a central sectional view of the pouring neck provided with a spout for pouring liquids from the receptacle;

Fig. 6 is a top plan view of Fig. 5;

Fig. 7 is a top plan view of the pouring neck and vent tube showing a slight modification; and

Fig. 8 is an end view of the construction shown in Fig. 7.

20 In the drawings the outer casing 1 is provided with an inner lining 2 constructed of tin or other suitable material, of light weight. The top of the outer casing is cut away to form a recess 3, and a guard plate 4 of sheet metal, or other suitable material of greater strength than the lining is arranged within the recess. The sides of the plate 4 are provided with upturned flanges 5 secured to the edges of the outer casing.

25 30 The pouring neck 6 is secured to the lining of the receptacle within the recess and is held in position by the guard. The pouring neck is of such a size that it terminates below the surface of the outer casing. A handle 35 7 is secured to the side walls of the recess and is adapted to be folded within the recess when the receptacles are packed. As shown in Figs. 1 and 2 of the drawings, the edge of the outer casing is cut away or beveled

40 near the recess as at 8, permitting the end of the guard to overhang the beveled portion of the side wall. In this manner the liquid may be poured from the receptacle with the recess serving as a trough and the 45 projecting edge of the guard prevents the liquid from running down the side of the receptacle. The same result can be obtained by extending the guard beyond the edge of the receptacle (not shown) and eliminating

50 55 60 65 the beveled portion 8, but this would interfere to some extent with packing.

Within the pouring neck there is arranged a number of radially disposed arms 9 supporting a central stud 10. The cap 11 of the receptacle carries a screw member 12 projecting from its lower surface and positioned to be received in the stud. The screw however can be made separable from the cap and an opening arranged in the cap for the projection of the screw. I find it advantageous to place a washer 13 between the walls of the pouring neck and the cap.

A vent tube 14 is arranged within the receptacle extending from the pouring neck 65 toward the opposite wall and positioned

near the top of the receptacle. The vent tube is provided with a vertical section 15 secured between two of the radially disposed arms (see Fig. 3). The radially disposed arms are suitably spaced to inclose the vent 70 tube, the position of the same being determined by the size of the vent tube, and they serve the additional function of providing definite passages for the flow of liquid from the receptacle and for the admission of air 75 to the vent tube.

In the construction shown in Figs. 5 and 6 I have provided a detachable spout 16 which is secured to the receptacle through the medium of screw member 17 received in the 80 stud and is provided with a spider 18 having the opening 19 in alignment with the opening in the stud. A collar 20 arranged upon the screw member engages the spider securing the spout in position. The lower end 85 21 of the spout is flanged to provide a seat and washer 22 is arranged between the seat and the pouring neck providing a liquid seal. The spout is employed where it is necessary to pour liquid slowly and confine the flow 90 to a restricted area such as in filling the gasolene tanks of automobiles.

In the construction shown in Figs. 7 and 8 the vent tube 23 is rectangular and the radial arms 24 are suitably spaced to inclose 95 walls of the vertical section 25 of the vent tube.

It will be seen that in this invention I provide a receptacle having no projecting parts, thereby permitting packing of a large number 100 of such receptacles without loss of space, without the employment of packing crates or the like. The construction for supporting the vent tube and securing the cap to the receptacle has been found to be very satisfactory. This construction has the further advantage of defining spaces for the outlet 105 of liquid and the admission of air.

What I claim is:—

1. A receptacle provided with a recess 110 portion upon one face, a pouring neck within the recess portion terminating below the outer surface of the receptacle, a guard plate within the recess, the side wall of the receptacle being cut away near said guard plate, the end of said guard plate overhanging said cut-away portion.

2. A receptacle provided with a recess portion in the top and a beveled edge near the said recessed portion, a filling neck within the recess portion terminating below the outer surface, a guard plate within the recess overhanging the beveled edge.

3. A receptacle comprising an inner lining, and an outer covering, a portion of 125 said outer covering being cut away on one face of the receptacle, and a beveled edge near said cut out portion, a relatively thin guard member within the cut out portion and overhanging said beveled edge, flanges 130

formed on the guard member secured to the edges of the outer covering, and a filling neck within the cut out portion of less height than the thickness of the outer covering.

4. A receptacle comprising an inner lining, and an outer covering, a portion of said outer covering being cut away on one face of the receptacle, and a beveled edge near 10 said cut out portion, a guard plate within the cut out portion covering the inner lining, flanges formed on the guard plate secured to the edges of the outer covering, one edge of the guard plate overhanging said 15 beveled edge, and a filling neck within the cut out portion terminating below the outer surface of the receptacle.

5. A receptacle provided with a pouring neck projecting beyond the top, a plurality 20 of radially disposed arms within the neck, a centrally disposed stud supported by said radially disposed arms, a vent tube extending within the receptacle secured to and confined between a pair of said radially disposed arms, a cap covering said pouring neck, and a screw for securing said cap in 25

position, said screw engaging said centrally disposed stud.

6. A receptacle provided with a pouring neck located near the front edge, a plurality 30 of radially disposed arms arranged within the neck and constituting divisions, a centrally disposed screw threaded stud supported by said radial arms, a cap provided with a centrally disposed screw for engagement with said stud, and a vent tube within 35 the receptacle, one end thereof being arranged within one of said divisions, the walls of the vent tube being inclosed by said radially disposed arms.

7. The combination with a receptacle provided with a pouring neck, radial arms arranged within the pouring neck, and a central stud supported by said radial arms, of a 40 spout detachably secured to said neck, supporting means within the spout, and a screw passing through said pouring means and engaging said stud.

Signed at Mount Joy in the county of Lancaster and State of Pennsylvania this 50 2d day of March, 1917.

CLARENCE SCHOCK.
